UNITED STATES PATENT OFFICE.

ROY ALEXANDER WEAGANT, OF DOUGLAS MANOR, NEW YORK, ASSIGNOR, BY MESNE ASSIGNMENTS, TO RADIO CORPORATION OF AMERICA, A CORPORATION OF DELAWARE.

METHOD AND APPARATUS FOR RADIOSIGNALING.

Application filed February 7, 1919. Serial No. 275,554.

To all whom it may concern:

Be it known that I, ROY ALEXANDER WEAGANT, a citizen of the United States, and resident of Douglas Manor, county of Queens, city and State of New York, have invented certain new and useful Improvements in a Method and Apparatus for Radiosignaling, of which the following is a specification, accompanied by drawings.

This invention relates to a method and apparatus for radio signaling, with reference more particularly to minimizing the interference of static disturbances in radio reception.

In my co-pending application Serial No. 181,458 I have set forth my discoveries in regard to the nature of heterogeneous disturbances and disclosed methods and apparatus for discriminating between such static waves which seem to behave as if propagated in a vertical direction and signal waves from a desired direction. The illustrative static eliminating apparatus shown in said co-pending application depends on the horizontal separation of antennæ to receive horizontally propagated signal waves as out of phase currents, and vertically propagated static waves as inphase currents.

In working with various forms of apparatus based upon my discoveries, I have observed certain phenomena which indicated that static impulses may be regarded as vertically propagated disturbances having relatively short wave length, so short in fact that I have been able to obtain wave length spacing equal to an appreciable fraction of a static wave length, with antennæ separated vertically by a distance of about twenty-five feet, more or less.

This further discovery in regard to the nature of static disturbances, in connection with my original discoveries, has enabled me to devise methods and apparatus for minimizing or reducing the effect of static interference in radio reception, which obviate the mechanical and electrical inconveniences of antenna systems widely spaced in a horizontal direction, because in accordance with the present invention, all the necessary apparatus may be conveniently assembled and operatively associated at the receiving station itself, within comparatively small space.

Instead of receiving signal waves successively and static waves simultaneously, my

present method consists in receiving signal waves simultaneously, and static waves successively in associated portions of an antenna system, and as before utilizing the relative difference of phase between the resulting currents to select the desired current. For retaining the signals, the simultaneous effects are combined cumulatively and the successive effects are combined differentially.

Suitable apparatus for carrying out my method of operation is shown in the accompanying drawings, in which—

Figure 1 is a diagrammatic representation of a preferred form of associated antennæ or portions of an antenna system operative in accordance with my invention; and

Figure 2 is a similar view of a modification.

Referring to the drawings, A and B represent two associated antennæ or portions of an antenna system preferably in the form of loops, although other suitable forms of antennæ may be provided. These loops may be of any convenient size and as shown in the drawing are assumed to be at different heights with reference to the ground and in the same or substantially parallel vertical planes, although they may diverge from the vertical to a certain degree and still be considered substantially vertical within the principles of my invention.

The loops A and B are preferably and conveniently superposed, one substantially above the other, although actual superposition is not essential, and they may be separated horizontally in the direction of desired reception if desired, provided that for electrical purposes they are circumstanced or arranged at substantially the same distance from the source from which signal waves are being received, so that said waves are received substantially simultaneously and set up in phase currents in the antennæ A and B.

I have found, as hereinbefore stated, that with a vertical separation of even twenty-five feet between the centers of the loops A and B, the static waves appear to be received successively and set up out of phase currents in the loops, and good results are obtained in more or less cancelling static by associating the loops so that they oppose one another while retaining the signal.

Although signal waves are ordinarily re-

ceived from horizontal directions, they may however be propagated in a general vertical direction, from an aeroplane for instance, and in such case, both signal and static waves 5 would be received in substantially the same general vertical direction. The signal waves may still be considered as substantially simultaneously received in my system under such circumstances, because the vertical separation of the antennæ A and B contemplated by me, although I can place no exact limits, is too small to equal an appreciable fraction of a wave length of signal waves which are relatively long compared to static 15 wave length, even as used in aeroplane signaling, so that the currents due to signals are still substantially in phase, or at least that the phase differences are of different orders.

20 Any suitable and desirable means may be provided for associating the antenna portions A and B in such manner that the static and signal currents may be selectively combined, and in this instance I have shown a 25 radio goniometer associated with said antenna, because that is a convenient and delicately adjustable instrument adapted to my purposes.

The loops A and B are connected to the 30 fixed coils C and D of the goniometer and provided with suitable variable tuning inductances E. Variable condensers F are preferably connected in circuit at the mid-points of the coils C and D and the loops 35 A and B are preferably tuned to the same frequency, that is, to the wave length of the signal waves to be received. The loops A and B are also preferably ungrounded.

The movable coil G of the goniometer is 40 pivoted about the axis H and the variable condenser J is connected in circuit therewith as shown. A suitable detector circuit K is preferably coupled to the circuit of the coil G by means of the coupling coils L and M. 45 So far as my observations have gone, the vertical separation of the loops does not have to be large in order to constitute an appreciable fraction of a static wave length, and even with loops about four feet in 50 diameter, having their centers separated vertically about 25 feet, I have found that the static currents received were of different phase while the signal current received were of the same phase, so that the static currents could be balanced out to a very large 55 extent and the signals retained. I am not yet prepared to state my conclusions as to the wave length of static waves, or whether it is uniform or variable, or through what 60 range it may vary, if it is variable, but I have conclusively demonstrated that static disturbances have short wave length, and vertical separation of a comparatively short 65 distance between antenna portions will give phase differences comparable to those which

are produced by signal waves but require long distances when horizontal separation is used.

In order that the antenna portions A and B may be affected more nearly simultaneously by waves from aeroplanes, not immediately overhead, or by signal waves of distorted wave front, the two loops may be adjusted so as to be not exactly one over the other but to be approximately parallel to 70 the wave front of the received wave, and also made rotatable together so as to bring their planes into or parallel with the line of reception.

In the modification shown in Figure 2, 80 antennæ A' and B' are shown in the form of horizontally extending linear oscillators having tuning elements in the form of variable inductances P and variable condensers Q. Coupling coils N and O are provided for coupling the antennæ A' and B' to the circuits of the goniometer and the remainder of the figure is similar to Figure 1.

I claim and desire to obtain by Letters Patent the following:

1. The method of minimizing static interference in radio transmission, which consists in receiving signal waves simultaneously and static waves successively in different portions of an antenna system, and utilizing 95 the relative phases between the resulting currents to select the desired current.

2. The method of minimizing static interference in radio transmission, which consists in receiving signal waves simultaneously and static waves successively in different portions of an antenna system as waves of the same frequency, and utilizing the relative phases between the resulting currents to 100 select the desired current.

3. The method of minimizing static interference in radio transmission, which consists in receiving signal waves simultaneously and static waves successively in a plurality of antenna portions as waves of the same 110 frequency, at least one antenna portion being ungrounded, and utilizing the relative phases between the resulting currents to select the desired current.

4. In radio reception, the method of minimizing static interference, which consists in receiving signal waves as currents substantially in the same phase and static impulses as currents substantially in opposite phase in a plurality of antennæ, and selectively 115 utilizing the desired one of said currents.

5. The method of minimizing static interference in radio transmission, which consists in discriminating between waves of definite period reaching different portions of a receiving system substantially simultaneously and heterogeneous waves arriving successively, and detecting the first named waves.

6. The method of minimizing static interference in radio transmission, which consists 120

in discriminating between waves of definite period reaching different portions of a receiving system substantially simultaneously and heterogeneous waves arriving successively, and selectively combining the currents due to said different waves.

7. The method of minimizing static interference in radio transmission, which consists in discriminating between waves of definite period affecting different portions of a receiving system substantially simultaneously and heterogeneous waves affecting said portions successively, by combining cumulatively the simultaneous effects and combining differentially those which are successive, and detecting such first-named defects.

8. The method of minimizing static interference in radio transmission, which consists in discriminating between waves of definite period affecting different portions of a receiving system substantially simultaneously and heterogeneous waves affecting said portions successively, by selectively combining the said simultaneous and successive effects, and detecting one of said effects.

9. The method of minimizing static interference in radio transmission, which consists in locating and adjusting a plurality of antenna circuits in such manner that static effects will produce therein currents dissimilar in phase and signal waves will produce therein currents similar in phase, combining differentially said currents dissimilar in phase, combining cumulatively said currents similarly in phase, and detecting the presence of said last named currents.

10. The method of minimizing static interference in radio transmission, which consists in locating and adjusting a plurality of antenna circuits in such manner that static effects will produce therein currents dissimilar in phase and signal waves will produce therein currents similar in phase, selectively combining all of said currents and detecting the desired one of said currents.

11. The method of minimizing static interference in radio transmission, which consists in causing the received signal to produce currents of similar phase in a plurality of circuits, causing heterogeneous disturbances to produce currents having a different relative phase, and selectively rejecting the last named effects by the aid of said distinction in phase difference.

12. The method of minimizing static interference in radio transmission, which consists in causing the received signal to produce currents of similar phase in a plurality of circuits, causing heterogeneous disturbances to produce currents having a different relative phase, and selectively rejecting one of said effects by the aid of said distinction in phase difference.

13. The method of minimizing static in-

terference in radio transmission, which consists in intercepting the signal waves at two points disposed at different heights with reference to the ground but at substantially equal distances from the source of waves, obtaining therefrom signal oscillations in phase with each other, combining the effect of these to produce signals, and combining the oscillations set up at the said two points by disturbing influences, out of phase, to neutralize each other.

14. The method of minimizing static interference in radio transmission, which consists in receiving static waves successively and signal waves substantially simultaneously from substantially the same general direction in a plurality of antenna portions, and selectively utilizing the desired one of the currents due to said different waves.

15. In radio signaling apparatus, means for receiving signal waves simultaneously and static waves successively, and means for utilizing the relative difference of phase between the resulting currents to select the desired current.

16. In radio signaling apparatus, a plurality of associated antenna portions tuned to the same frequency and so positioned one above the other and at equal distances from the source of signal waves as to receive signal waves simultaneously and static waves successively, and means for utilizing the relative difference of phase between the resulting currents to select the desired current.

17. In radio signaling apparatus, an antenna system having associated portions, at least one of which is ungrounded, said portions being so positioned one above the other and at equal distances from the source of signal waves as to receive signal waves simultaneously and static waves successively, and means for utilizing the relative difference of phase between the resulting currents to select the desired current.

18. In radio signaling apparatus an antenna system having associated portions tuned to the same frequency at least one of said portions being ungrounded, said portions being so positioned one above the other and at equal distances from the source of signal waves as to receive signal waves simultaneously and static waves successively, and means for utilizing the relative difference of phase between the resulting currents to select the desired current.

19. In radio signaling apparatus, a plurality of ungrounded associated antenna portions so positioned one above the other and at equal distances from the source of signal waves as to receive signal waves simultaneously and static waves successively, and means for utilizing the relative difference of phase between the resulting currents to select the desired current.

20. In radio signaling apparatus, a re-

ceiving system having a plurality of associated portions, means for discriminating between waves of different period reaching different portions of said receiving system 5 substantially simultaneously and heterogeneous waves arriving successively, and means for detecting the first-named waves.

21. In radio signaling apparatus, a receiving system having a plurality of associated portions, means for discriminating between waves of definite period reaching different portions of said receiving system substantially simultaneously and heterogeneous waves arriving successively, and means for 10 selectively combining the currents due to 15 said different waves.

22. In radio signaling apparatus, a receiving system having a plurality of associated antenna portions, means for discriminating 20 between waves of definite period affecting different portions of said receiving system substantially simultaneously and heterogeneous waves affecting said portions successively, and means for cumulatively combining the simultaneous effects and differentially combining those which are successive, and means for detecting the first-named effects.

23. In radio signaling apparatus, a receiving system having a plurality of associated antenna portions, means for discriminating between waves of definite period affecting different portions of said receiving system substantially simultaneously and 35 heterogeneous waves affecting said portions successively, means for selectively combining the said simultaneous and successive effects, and means for detecting one of said effects.

24. In radio signaling apparatus, an antenna system having ungrounded associated portions arranged at different elevations but at substantially the same distance from the source of signals to be received, and means 45 for detecting signals including means for balancing out the effects of static disturbances.

25. In radio signaling apparatus, an antenna system having associated portions 50 tuned to the same frequency and arranged at different elevations but at substantially the same distance from the source of signals to be received, and means for detecting signals including means for balancing out the 55 effects of static disturbances.

26. In radio signaling apparatus, means for reducing the effect of static disturbances in radio transmission, comprising a plurality of antennæ located at a suitable distance apart vertically to be affected successively by static impulses thereby producing static currents therein dissimilar in phase, means for differentially combining said static currents dissimilar in phase and for 60 cumulatively combining the currents similar 65

in phase due to signal waves, and means for detecting the presence of said last-named currents.

27. The method of minimizing static interference in radio transmission, which consists in receiving in an antenna system, signal impulses as currents with one order of phase difference, and static impulses as currents with a greater order of phase difference, and selectively combining said currents to neutralize a desired one of said effects.

28. In radio signaling apparatus, means for receiving signal impulses as currents with one order of phase difference and static 80 impulses as currents of a greater order of phase difference, and means for selecting a desired one of said currents.

29. In radio reception, the method of minimizing static interference, which consists in simultaneously receiving signal waves from one direction as currents substantially in the same phase, receiving static impulses from another direction at right angles thereto as currents substantially in 90 opposite phase, balancing out the static and retaining the signal currents.

30. In radio reception, the method of minimizing static interference, which consists in simultaneously receiving signal 95 waves from one direction as currents substantially in the same phase, receiving static impulses from another direction at right angles thereto as currents substantially in 100 opposite phase, balancing out currents due to one kind of wave and retaining the other currents.

31. In radio reception, the method of minimizing static interference, which consists in simultaneously receiving horizontally 105 propagated signal waves as currents substantially in the same phase, receiving vertically propagated static impulses as currents substantially in opposite phase, balancing out the static and retaining the signal currents.

32. In radio reception, the method of minimizing static interference, which consists in simultaneously receiving horizontally propagated signal waves as currents substantially in the same phase, receiving vertically propagated static impulses as currents substantially in opposite phase, balancing out currents due to one kind of wave and retaining the other currents.

33. In radio reception, the method of minimizing static interference, which consists in simultaneously receiving signal waves as currents substantially in the same phase, receiving static impulses as currents substantially in opposite phase in a plurality 115 of antennæ, cumulatively combining said signal currents and differentially combining said static currents.

34. In radio reception, the method of minimizing static interference, which con-

sists in simultaneously receiving signal waves as currents substantially in the same phase, receiving static impulses as currents substantially in opposite phase in a plurality of antennae, tuned to the same wave length, and selectively utilizing the desired one of said currents.

In testimony whereof I have signed this specification in the presence of two subscribing witnesses.

ROY ALEXANDER WEAGANT.
